GOLF CUP

George F. Wales, Kenmore, N. Y.

Application May 26, 1944, Serial No. 537,423

4 Claims. (Cl. 273—34)

1

This invention relates to cups for use in golf course putting greens into which golf balls are directed to terminate the play at each hole. Cups are also used in practice games.

As heretofore constructed golf cups have consisted of tubular receptacles having an internal spider-like portion for supporting the flagstaff at a depth of at least 4" from the top of the hole as established by the rules of the game. This spider has a socket in the center of the cup to accommodate a bamboo flagpole which projects upward from the hole at an approximate height of from four to seven feet above the green to indicate to approaching players the position of the hole.

While the rules of the game require that the flagstaff stand upright in the hole it is rather exceptional to find one in an upright position. This is due to the wear and tear which the bottom of the staff is subjected to continually during the golfing season. In many courses it is not unusual for every flag on the course to be withdrawn and replaced in its cup one hundred times a day and even though many staffs are equipped with ferrules, these come loose and the flagstaff assumes an angular position. Thus a player in approaching a hole may find that the staff is leaning toward him and should his shot be accurately played the ball instead of dropping into the cup would be interfered with.

Golf cups as heretofore constructed with the referred to spider have depended upon the natural drainage of the greens in which they were implanted to carry off any water which had accumulated in the cup. The cup tube to provide for this has been made approximately twice as long as the cup itself required and the spider was located about midway of the tube. Preparatory to placing the cup in a green a hole has been formed to accommodate the full length of the tube so that when inserted a well existed below the spider midway of the tube and the bottom of the hole.

The spider has been comprised of spokes attached to the inner diameter of the tube and supporting the socket for the flagstaff. Between the spokes were openings through which water passed into the lower well when it rained or the green was sprinkled. Often the greens become soaked with water and the cups fill up and in such instances it takes quite a while for the water to drain out to a level where the ball may be played into it without getting wet. Because of the open construction of these cups they have usually become muddy in wet weather and play-

2

ing a ball into them has been disagreeable as in retrieving the ball the fingers were soiled and the ball had to be wiped clean.

The principal object of this invention is to provide a cup for a golf hole which at all times is free from water, dirt, sand, or other foreign substance so that when the player plays his ball into the hole it does not become wet or soiled.

Another object is to provide an improved means for supporting the flagstaff in the hole.

Still another object is to provide a method of joining the flagstaff to the hole lining in such manner that the staff cannot lean so that it bears on the lip of the hole thus making the hole irregular and larger than the 4 1/4" specified by the rules of the game.

A further object is to set the flagstaff away from the center of the hole and toward the side farthest away from the direction in which the ball is being played to the hole, thus making the entrance to the hole as open as possible, so that a ball being played from an approaching distance to the hole will have the best possible chance of entering the hole.

Another object is to provide a means of locating two nesting linings or cups so that the flagstaff will always be farthest away from the direction in which the majority of approach shots are played to the hole.

Another object is to provide a means of lifting the ball or balls out of the hole on practice greens. The balls are played into the hole with the inner cup and flagstaff in it and the player lifts the staff and cup containing the balls and empties the cup without bending.

Another object is to provide a golf cup which requires the digging of a hole in the green only the depth of the hole required in the rules and one which is closed at the bottom and requires no drainage.

Another object is to provide a golf cup with the flagstaff in coaxial relation with the cup but so arranged that the staff is formed to be supported at the side of the cup and thus provide an entrance to the hole as open as possible.

Other objects and advantages of the invention will more fully and clearly appear from the description and claims hereinafter.

50 In the accompanying drawing:

Fig. 1 is a perspective view of my improved double golf cup as it appears in a putting green.

Fig. 2 is a vertical section of the same as taken on line 2—2 of Fig. 1.

Fig. 3 is a vertical section of the inner cup

separated from the outer cup with the view taken on line 3—3 of Fig. 2.

Fig. 4 is a top plan view of the outer cup looking into the hole after the inner cup has been withdrawn as indicated by line 4—4 of Fig. 2.

Fig. 5 is a top plan view of the inner cup taken on line 5—5 of Fig. 3.

Fig. 6 is a vertical section of the outer cup showing its position on the ground and how no drainage is required.

Fig. 7 is a vertical section of my double cup with the flagstaff formed to be in coaxial relation with the cup.

Fig. 8 is a sectional plan view of the inner cup shown in Fig. 7 as taken on line 8—8 of Fig. 7.

In the following description similar characters of reference indicate like parts in the several figures of the drawings.

In Fig. 1 the numeral 10 represents a putting green, 11 the hole in the green and 12 the flagstaff attached to the wall of an inner cup as illustrated in Figs. 3 and 5.

The details of a preferred form of the organization of parts as illustrated in Fig. 1 is shown in Fig. 2 whereby 13 is an outer cup or hole lining having a closed bottom 14. The cup is so formed that the side walls extend below the level of the bottom, as indicated by numeral 15.

Fig. 6 shows the outer cup 13 embedded in hole 16 which has been cut out of the green and the earth removed to the bottom 17 of the hole. The lower rim 18 of the outer cup rests on the earth as shown to prevent the cup from being forced lower into the hole than the official rules of the game provide. Top edge 19 of the cup when in its proper position is approximately 1" below the lip of the hole so that a fast running ball will strike the soil rather than the cup.

Numerical 20 indicates an annular well which is narrower than the diameter of a golf ball and is so constructed as to catch any water or moisture which might remain in this cup after the inner cup which will be described subsequently is removed.

Numerical 21 indicates a golf ball elevated above the well as it rests on the inner surface 22 of the cup.

Fig. 2 illustrates how my inner cup 23 is placed freely into outer cup 13 in such manner that the configuration of the base of the outer cup is closely followed by the inner cup. Due to the close arrangement of these two cups it is obvious that the moisture which could accumulate between the inner and outer cup would be so small that when the inner cup is removed the slight amount of moisture would be barely noticeable in the well 20 of the outer cup.

In order to assist in keeping moisture or foreign substances from getting into the space between the two cups I provide an outwardly formed flange 24 which rests approximately flush with the top of the hole in the green.

In Fig. 3 the inner cup is shown removed from the outer cup and as indicated by numeral 25 flagstaff 12 is welded or otherwise attached to the inside of the wall 26 of the inner cup.

In order that the flagstaff will be positioned at the rear side of the cup, or at the side of the cup farthest away from the teeing ground, so that a substantially open hole faces the player, I provide on the outer cup means for insuring that this position is maintained.

Although any number of methods may be devised to accomplish this I prefer to form a protuberance 27 upwardly into the well with which

companion protuberance 29 in the inner cup engages in order to permit the inner cup to be received properly in its outer cup.

Having thus described this particular organization of parts it is obvious that when the putting green is soaked with water either by rain or by having been sprinkled and with the cups in position as shown in Fig. 2 the inner cup collects practically all of the water which enters the hole. When the flagstaff and inner cup are removed from the hole the inner cup acts as the bowl of a ladle and carries out all of the water or foreign matter which might have fallen into the hole, the slight amount of excess water between the two cups then collecting in well 20.

The reason for placing flagstaff 12 at the outer side of the hole rather than in the center is to provide a comparatively complete hole into which the ball will fall on the rare occasions when unexpected shots drive the ball to the cup. By attaching the shaft securely to the inner cup, the flagstaff always stands in an upright position.

The rules of the game of golf are rather rigid 25 and its is problematical as to whether such a cup as previously described would be acceptable to the Rules Committee. I therefore have invented an alternative method of attaching the flagstaff to the inner cup, as illustrated in Fig. 7 30 whereby flagstaff 30 is attached to the wall of the inner cup but is formed as indicated by numerals 31 and 32 to bring the main staff 33 into coaxial alinement with the hole, otherwise this invention is the same as described above.

35 I claim:

1. A golf ball receptacle for a hole in a putting green comprising a cup having a cylindrical wall extending to within a short distance of the ground level and a closed bottom formed inwardly to provide an annular well between the cylindrical wall and said bottom and a removable internal cup having walls the full depth of the hole and being shaped to fit closely into said outer cup in such manner that the volume of space between the inner wall of the outer cup and the outer wall of the inner cup is less than the volume of said annular well.

2. The combination of a cylindrical liner for a hole in a golf putting green and a removable base cup attached to a flagstaff, said flagstaff being attached eccentrically of the center of said cup and means for registering the placing of said base cup in said liner so that the flagstaff is in the portion of the hole most remote from the teeing ground.

3. The combination of a cylindrical liner for a hole in a golf putting green and a removable base cup attached to a flagstaff, said flagstaff being attached eccentrically of the center of said cup and being bent above said cup to bring the main staff coaxial with said liner and means for registering the location of said base cup with relation to said liner, so that the attachment of said flagstaff to said base cup is in the portion of the hole remote from the teeing ground.

4. A fixed ball receptacle and a combined casual golf cup and marker combination for use in a hole in a putting green characterized by having 70 a flagstaff attached to the inside of the vertical wall of said cup, the mouth of said cup projecting above the soil level and being flared outwardly and the bottom of said cup having an annular well between the cylindrical wall and a bottom formed inwardly into said cup, said fixed

receptacle having a bottom and well conforming in shape to that of said cup.

GEORGE F. WALES.
